DESIGN FOR A VELOCIPED

Bert J. Anderson, Hammond, Ind.

Application September 13, 1935, Serial No. 58,539

Term of patent 14 years

To all whom it may concern:

Be it known that I, Bert J. Anderson, a citizen of the United States, residing at Hammond, in the county of Lake and State of Indiana, have invented a new, original, and ornamental Design for a Velocipede, of which the following is a specification, reference being had to the accompanying drawing, forming part thereof.

Figure 1 is a side elevational view of a velocipede, showing my new design;

Figure 2 is a rear elevational view of the frame;

Figure 3 is a front elevational view of the frame; and

Figure 4 is a top plan view of the frame.

I claim:

The ornamental design for a velocipede, as shown.

BERT J. ANDERSON.
